UNITED STATES PATENT OFFICE

128,176

DESIGN FOR A KEY RACK

Morris E. Rogat, Cleveland, Ohio

Application January 9, 1941, Serial No. 97,902

Term of patent 7 years

To all whom it may concern:

Be it known that I, Morris E. Rogat, a citizen of the United States, residing at Cleveland, in the county of Cuyahoga, State of Ohio, have invented a new, original, and ornamental Design for a Key Rack, of which the following is a specification, reference being had through the accompanying drawing, forming a part thereof.

Figure 1 is a front elevational view of the key rack, showing my new design; and Figure 2 is a side elevational view thereof.

I claim:

The ornamental design for a key rack, as shown.

MORRIS E. ROGAT.
